Design No. 3,680, dated September 28, 1869.

DESIGN FOR A STOVE.

The Schedule referred to in these Letters Patent and making part of the same.

I, SAMUEL L. UTTER, of the city of Brooklyn, in the county of Kings, and State of New York, have invented and produced a new and original Design for a Base-Burning Stove, of which the following is a specification.

The nature of my design is fully represented in the accompanying photographic illustration, to which reference is had.

What I claim as my invention, and desire to secure by Letters Patent, is—

The design for a base-burning stove herein set forth.
